PAGE 2

Fig. 2

Fig: 3

Figure 1 is a front view of the powder feeder, embodying my new design;

Figure 2 is similar to Figure 1 but taken from the left side, the right side being substantially the same; and

Figure 3 is similar to Figure 1 but taken from the rear.

The circumferential shape of the funnel element is circular.

The right side is similar to the left side. The essential features of my design reside in the portions shown in full lines.

I claim:

The ornamental design for a powder feeder, as shown and described.
